ABSTRACT

A quick starting magnetron having two cathodes, one of low heat inertia and thermally emissive for starting purposes and the second of high heat inertia positioned between the magnetron anode and the first cathode. The second cathode is apertured to allow electrons to pass through from the first cathode and is arranged to partially shield the first cathode from electron bombardment during normal running of the magnetron.

QUICK STARTING MAGNETRON WITH SHIELDED CATHODE

This invention relates to magnetrons and has for its object to provide improved quick starting magnetrons of high power capability.

It is well known to obtain quick starting qualities in a magnetron by making the cathode structure of such design that it will heat up very rapidly to emission temperature from cold. However, known cathode structures of such design have the defect that because, after starting and during normal running of a magnetron, the cathode is subjected to considerable electron bombardment, the cathode temperature tends to rise substantially and this sets an undesirable limit to the power which can be safely handled. Indeed it is not uncommon to make magnetrons with heated cathodes the heaters of which are switched on only during starting, electron bombardment during running serving alone to maintain the cathode at normal operating temperature. To be quick starting a magnetron must have a thermionic cathode of low heat inertia and such a cathode is necessarily of poor heat dissipation properties — usually through being of poor heat conductivity — and accordingly, if, after starting, the cathode is subjected to too much additional heating by electron bombardment, the heat is unable to get away and the temperature rises to an unacceptably high level. This limits the power capability of the magnetron very severely and known quick starting magnetrons are limited in this way to power levels at which electron bombardment heating of the quick starting cathode will not cause its temperature to rise to the point at which it may be damaged or destroyed. The present invention seeks to lift this limitation and to provide improved quick starting magnetrons of higher power capability than comparable quick starting magnetrons known to the applicants.

According to this invention a quick starting magnetron has an anode, a first thermally emissive cathode structure of low heat inertia; and a second cathode structure of relatively high heat inertia positioned between said anode and said first cathode structure and apertured so as to allow electrons to pass therethrough from said first cathode structure into the space between the anode and the second cathode structure; said second cathode structure being positioned and dimensioned so as to at least partially screen the first cathode structure from electron bombardment during normal running of the magnetron.

Preferably the second cathode structure is given a sufficiently high secondary emission coefficient to ensure that practically all or the major part of the electron current required for magnetron operation is supplied by secondary electron emission.

The second cathode structure may be designed to be heated only by electron bombardment but, if desired, it may also be arranged to be heated electrically.

In a preferred embodiment the first cathode structure comprises a thin walled inner metal tube having a ring coating of thermionically emissive material thereon and said second cathode structure comprises, co-axial with said thin walled tube, a thick walled tubular structure apertured axially adjacent said ring coating. Electrical heating of the thin walled tube may be effected in any of a variety of known ways but preferably it is accomplished directly by passing heating current through it. In a preferred arrangement of this type a central

axial rod is provided inside and spaced from the thin walled metal tube; said rod is fixed at its outer end to an outer "end hat" of disc form which also locates the outer end of the thin walled tube and the outer end of the thick walled tubular structure; and an inner annular "end hat" surrounds said rod and locates the inner end of the thick walled tubular structure, means being provided for feeding heating current through a circuit including the axial rod, the outer end hat and the thin walled tube.

The last mentioned means preferably includes said support rod and an additional support which is hollow, e.g., cylindrical, surrounds said rod and supports both the inner end hat and the inner end of the thin walled tube. In such an arrangement the thick walled tubular structure must not short circuit the thin walled tube and therefore there must be an insulating gap in the electrical path from one end hat to the other through the tubular structure. This could be done by insulating one end of the tubular structure from the associated end hat but preferably the tubular structure is formed by two cylindrical sections separated one from the other, with the gap therebetween forming the aperture for electrons from the thin walled first cathode structure.

In this arrangement the support rod and additional support provide good thermal conduction paths from the thick walled structure to the exterior of the magnetron.

The invention is illustrated, by way of example, in the accompanying drawing which illustrates schematically, and so far as is necessary to an understanding thereof, a preferred embodiment.

The magnetron represented in the drawing is, except for the cathode arrangement, a multi-cavity magnetron of well known form. Accordingly only the said arrangement is shown in any detail, the rest of the magnetron being represented merely by the inner ends, of the radial vanes which are fixed to the inside of the anode cylinder to provide a plurality of resonant cavities in accordance with well known magnetron practice.

Referring to the drawing, V are the inner ends of two of the vanes which project radially inwards from the cylindrical anode of the anode system of a multi-cavity magnetron. Axially situated within the anode system is a cathode arrangement which comprises a quick starting first cathode structure and a second main cathode structure which acts also as an electron shield to prevent overheating of the quick starting cathode and its support by bombardment by returning electrons when the magnetron is in normal running operation.

The quick starting cathode structure is constituted by a ring 1 of suitable thermionic emissive material on the outer surface of a thin-walled metal tube 2 at about the middle of the length thereof. Because of the thinness of the wall of the tube 2, the quick starting cathode is of low thermal inertia. For the same reason, however, it is unable to conduct heat away quickly for dissipation.

Co-axially surrounding the quick starting cathode is a combined main cathode structure and electron shield. This consists of two similar thick walled metal tube portions 3, 4 on the outer surfaces of which are deposits 5, 6 of material capable of secondary electron emission. If desired material capable of primary electron emission may also be deposited over all or part of the surface. There is, between the adjacent ends of the portions 3, 4, a gap or aperture 7 which is opposite the

emissive ring 1 and through which electrons from said ring can pass into the working electron space inside the anode system.

8 and 9 are metal so-called "end hats" which locate the ends of the cathode structures and an axial metal rod 10 extends up to and is connected to the upper end hat 8. 11 represents a main electrically conductive support for the cathode structure as a whole and the lower end hat 9 sits on this support. Heating of the quick starting cathode is effected electrically by passing heating current through a heating current circuit consisting of the rod 10, the upper end hat 8 the thin walled tube 1 and the support 11.

An arrangement as illustrated enables a quick starting magnetron of substantially high power capability to be obtained because, owing to the electron shielding of the thin walled cathode structure provided by the tube portions 3 and 4, over-heating of the thin walled tube 2 and the emissive cathode material 1 carried thereby will not now occur. Additionally the rod 10 and support 11 provide a good thermal conduction path for heat from the thick walled structure 3, 4 to the exterior of the magnetron so as to permit operation of the magnetron at levels of power which cause substantial back heating of the structure 3, 4 by electron bombardment.

The design may be such that the heating current is kept switched on after starting or it may be such that the heating current is switched on only for starting and then switched off. As illustrated the main cathode (3, 5 - 4, 6) is not provided with any heating means (other, of course, than by electron bombardment by returning electrons) but, if desired, electrical heating for this cathode may be arranged for in any convenient manner known per se and the design may be such that this electrical heating is switched on only during starting or, alternatively, is kept on after starting.

We claim:

1. A quick starting magnetron including an anode; a first thermally emissive cathode structure of low heat inertia; and a second cathode structure of relatively 40 high heat inertia positioned between said anode and said first cathode structure; a continuous circumferential aperture provided in said second cathode so that said second cathode is formed in two axially separated portions, the aperture permitting electrons to pass 45 therethrough from said first cathode structure into the space between the anode and the second cathode structure; said second cathode structure being positioned and dimensioned so as to at least partially screen the first cathode structure from electron bombardment 50 during normal running of the magnetron.

2. A quick starting magnetron according to claim 1 wherein the second cathode structure is given a sufficiently high secondary emission coefficient to ensure that the major part of the electron current required for 55 magnetron operation is supplied by secondary electron emission.

3. A quick starting magnetron according to claim 1 wherein the second cathode structure is arranged to be

heated only by electron bombardment.

4. A quick starting magnetron according to claim 1 wherein the first cathode structure is arranged to be heated electrically.

5. A quick starting magnetron according to claim 1 wherein the first cathode structure comprises a thin walled inner metal tube having a ring coating of thermionically emissive material thereon and said second cathode structure comprises, co-axial with said thin walled tube, a thick walled tubular structure apertured axially adjacent said ring coating.

10 6. A quick starting magnetron according to claim 5 wherein the thin walled tube is electrically heated by passing heating current through it.

7. A quick starting magnetron according to claim 6 wherein a central axial rod is provided inside and spaced from the thin walled metal tube; said rod is fixed at its outer end to an outer "end hat" of disc form which also locates the outer end of the thin walled tube 20 and the outer end of the thick walled tubular structure; and an inner annular "end hat" surrounds said rod and locates the inner end of the thick walled tubular structure, means being provided for feeding heating current through a circuit including the axial rod, the outer and hat and the thin walled tube.

25 8. A quick quick starting magnetron according to claim 7 wherein the means for feeding heating current includes said support rod and an additional support which is hollow cylindrical, surrounds said rod and supports both the inner end hat and the inner end of the thin walled tube and wherein there is an insulating gap in the electrical path from one end hat to the other through the tubular structure.

30 9. A quick starting magnetron as claimed in claim 1 wherein the aperture is provided mid-way along the axial length of said second cathode structure.

35 10. In a quick starting magnetron having an anode space defining a plurality of magnetron cavities, the combination of:

a first cathode structure disposed within said anode space and comprising a thin wall tube having a ring of thermally emissive material on its outer surface; conductor means engaging opposite ends of said tube for supporting said tube and passing heating current therethrough whereby to provide quick starting of the magnetron; and

a second cathode structure surrounding and spaced from said tube and having aperture means aligned with said ring of thermally emissive material to allow electrons to pass into said anode space, said second cathode structure including thick wall tube portions on either side of said aperture means shielding said thin wall tube from bombardment from returning electrons, said conductor means engaging said tube portions for conducting heat therefrom to the exterior of the magnetron, and said tube portions being provided with exterior coatings of secondary emission material.
